UNITED STATES PATENT OFFICE

LOUIS DVILNSKY, OF BROOKLINE, MASSACHUSETTS

BASEBOARD RADIATOR

Application filed March 12, 1930. Serial No. 435,110.

This invention relates to a radiator for heating purposes adapted to be used either with steam or hot water.

The object of the invention is to provide a radiator which can be installed in the place of the ordinary baseboard in a room, doing away with the unsightly and bulky radiators at present used, and utilizing the space now taken up by such radiators for other purposes.

10 The invention consists of a baseboard radiator constructed as hereinafter set forth and particularly as pointed out in the claims.

Referring to the drawings:—

Fig. 1 is a front elevation of a pair of 15 baseboard radiators connected together and broken away to save space in the drawings.

Fig. 2 is a plan view of the radiators illustrated in Fig. 1.

Fig. 3 is a vertical section taken on line 20 3—3, Fig. 1.

Like numerals refer to like parts throughout the several views of the drawings.

In the drawings, 5 and 6 are two radiators, duplicates of each other, and joined together 25 by nipples 7 and 8. Each of the radiators 5 and 6 comprise a front section 9 and a rear section 10, these sections forming together a rectangular radiator section. The sections 9 and 10 are spaced apart by an air chamber 11 which has baffle plates 12 therein, positioned in staggered relation to each other. These baffle plates extend the entire length 30 of the sections 9 and 10. The air chamber 11 is inclined vertically at an angle from the rear toward the front and is partly closed at the top by a grille 13, said air chamber being open at the bottom to admit air from beneath the sections 9 and 10.

Heated fluid is admitted to the rear section 40 10 through a pipe 14 and passes into the section 9 through nipples or pipes 15. The heated fluid passes out of the section 9 into the front section of the radiator 6 through the pipe 8, and the heated fluid passes from 45 the rear section 10 of the radiator 5 into the rear section of the radiator 6 through the pipe 7, and out of the front section of the radiator 6 through pipe 19.

A sheet of asbestos 16 is interposed between the backs of the radiators 5 and 6 and

the wall 17 of the room in which the radiators are installed. A base molding 18 is fastened to the wall 17 and rests on the top of the rear section 10.

The heating fluid passes through the radiators 5 and 6 and hot air passes upwardly through the air chamber 11 in the direction of the arrows *a* and also passes upwardly along the front face of the front section 9, as shown by the arrow *b*.

The radiator of this invention forms a member which is rectangular in cross section and can be inserted in the place of a baseboard, the same performing the function of a baseboard and having a similar appearance, except that it is thicker. In practice the thickness of the radiator would be about two inches where the baseboard is one inch in thickness.

A large amount of radiating surface is 70 supplied by the radiator of this invention, by both of the walls of the chamber and front wall of the section 9. The baffles 12 are inserted in the chamber 11 and positioned in staggered relation to each other, in order to 75 delay and divert the air in its passage from the bottom out of the top of the radiator, whereby the air will have sufficient time to become thoroughly heated before emerging through the grille 13.

One of the principal advantages of this invention resides in the fact that in addition to doing away with the unsightly and bulky radiators at present used, the radiator can be extended across the entire width or length 85 of a room without taking up much if any more space than the present baseboard, and by so doing, the air of the entire room passes to the bottom of the radiator up through the radiator and up towards the top of the room 90 and back to the other end of the room throughout the entire width of the room, thus giving complete circulation of air and heating all the air in the room much more efficiently than the radiators in present use, 95 which only occupy a small portion of the width or length of the room in which they are located.

Another great advantage to be obtained by the use of the radiator of this invention is 100

- that being located near the floor and extending across the entire width or length of the room, a much more perfect circulation of the air in the room is obtained and the air at the bottom of the room, which is always coldest and dampest, will enter the radiator and be heated and then dispersed throughout the entire room. The advantage of this complete circulation and heating of the air in the room 10 renders it unnecessary to heat the radiator to such a high degree as where the radiator is short and located only in a portion of one side or end of the room, so that air being completely heated and circulated throughout 15 the entire room, the radiator does not have to be heated to such a high degree in order to make the room comfortable, and in order to do away with the dry heat which results from a high temperature radiator.
- 20 Another advantage secured by the radiator of this invention is that the air chamber 11, as particularly illustrated in Fig. 3, is inclined vertically from the rear toward the front of the radiator, so that the air as it 25 passes out of the radiator is directed away from the back of the radiator and consequently away from the wall of the room and any pictures or draperies which may be located above it. Thus the soiling of the curtains and of the walls and of the ceiling of 30 the room just above the radiator is entirely obviated. This is of great value as compared with the radiators in present use, in which the heated air passes from the radiator 35 directly up along the wall through the draperies and against the pictures and soils them in a short time after they are installed.

It will be understood that the usual valves for shutting off or admitting the steam or hot 40 water into the radiator will be used and also the well-known air valves, although these valves are not shown in the drawings, they being well known to those skilled in the art.

I claim:

- 45 1. A baseboard radiator having, in combination, two hollow sections spaced apart by an air chamber open at the top and bottom, baffle plates in said chamber positioned in staggered relation to each other, and means 50 to conduct heated fluid into and out of said sections.
2. A baseboard radiator having, in combination, two hollow sections rectangular in cross section positioned one in front of the 55 other and spaced apart by an air chamber, a pipe leading into and another pipe leading out of the upper part of one section, a pipe leading into and another pipe leading out of the lower part of the other section, and a 60 pipe connecting the bottom parts of said sections together, whereby heated fluid may be circulated through said sections.

In testimony whereof I have hereunto set my hand.
